UNITED STATES PATENT OFFICE.

WINFIELD SCOTT MARSHALL, OF CENTRALIA, ILLINOIS.

SADDLE-BAGS AND HAND-CASE.

SPECIFICATION forming part of Letters Patent No. 476,545, dated June 7, 1892.

Application filed March 26, 1891. Serial No. 386,492. (No model.)

To all whom it may concern:

Be it known that I, WINFIELD SCOTT MARSHALL, a citizen of the United States, residing at Centralia, in the county of Marion and 5 State of Illinois, have invented certain new and useful Improvements in Combined Saddle-Bags and Hand-Cases, of which the following is a specification.

My invention relates to a combination saddle-bags and hand-case designed specially for 10 the use of physicians; and its object is, primarily, to provide a convenient handle device whereby the two sections or boxes of the device may be carried by a single handle.

15 The invention consists in the combination, with two independent boxes or cases, of a divided or bifurcated handle adapted for attachment to both boxes, as will be hereinafter described.

20 In the drawings, Figure 1 is a perspective view of my improved saddle-bags and hand-case, the parts being in position as a hand-case. Fig. 2 is an end view of the same.

The two boxes or cases are indicated by the 25 numerals 1 and 2 and are connected by a strap 3, one end of which is attached in any preferred manner to each of the said boxes.

30 4 indicates a handle, the ends of which are split, bifurcated, or divided to form securing-ears 5 and 6. The ears or ends 5 are permanently secured by rivets to the box 1 or to a portion of the strap 3 adjacent thereto, and the other ears 6 are formed with slits 7, adapted to take over catches, buttons, lugs, or other

securing devices 8, projecting from the case 2. 35 The boxes 1 and 2 may or may not be provided with end-securing catches 9.

The operation and utility of my improvement are obvious from the drawings and the foregoing description. When the device is 40 intended for use as saddle-bags, the ears 6 are disconnected from the fastenings 8 to allow the boxes to be separated, and when it is desired to form a hand-case the boxes are placed together back to back, the strap 3 being folded 45 between them, as shown, and the ears or ends 6 of the handle are engaged with their fastenings 8.

I do not restrict myself to any special mode of attaching the handle to the case 1, but desire to include all constructions of handle that 50 may be included within the terms of the following claim.

I claim—

In a saddle-bags and hand-case, two boxes 55 connected by a strap and adapted to be placed together back to back, in combination with a handle the ends of which are divided and secured permanently to one box and adapted to engage fastenings on the other box, substan- 60 tially as set forth.

In witness whereof I have hereto set my hand in the presence of two attesting witnesses.

WINFIELD SCOTT MARSHALL.

Attest:

N. S. WRIGHT,
ROBERT J. MOORE.
